UNITED STATES PATENT OFFICE.

HENRY B. HIGGINS, JR., OF DENVER, COLORADO.

SUPPLEMENTARY FUEL-FEEDING DEVICE FOR INTERNAL-COMBUSTION ENGINES.

Application filed September 8, 1925. Serial No. 55,182.

My invention relates to improved means for supplementing the regular fuel supply of an internal combustion engine at such times as an auxiliary supply of fuel becomes 5 desirable, as for starting the engine, and for causing it to accelerate rapidly when the throttle is quickly opened.

An object of my invention is to provide such a device which positively cuts off the 10 supplemental fuel supply except at those times when it is needed.

A further object of my invention is to provide such a device which may be actuated by the vacuum created by the carburetor choke- 15 valve, to admit a supplemental supply of fuel when the engine is operated with said choke-valve closed.

A further object of my invention is to provide such a device which may be operated 20 manually to admit a supplemental supply of fuel when desired.

A further object of my invention is to provide such a device which may be operated in conjunction with the throttle to admit a supplemental quantity of fuel for a predetermined period of time following the opening 25 of said throttle.

A further object of my invention is to provide such a device which may be operated in 30 any one, or two, or all three of the aforesaid ways.

A further object of my invention is to provide such a device which introduces its supplemental fuel supply into the intake pipe of 35 the engine in the form of a fine mist.

A further object of my invention is to provide such a device which at all times admits a small jet of atmospheric air into the intake pipe of the engine.

40 Further objects of my invention are to provide such a device which is inexpensive to manufacture and easy to install.

My invention may be embodied in various forms to suit different conditions. Those 45 forms which I deem most practical for general use are illustrated in the accompanying drawing wherein—

Figure 1 is an end elevation of my invention secured between the carburetor and the 50 intake pipe of an internal combustion engine, with which units it cooperates; Figure 2 is a longitudinal section through my invention, taken on the indicated line 2—2 of Figure 1; Figure 3 is a partial longitudinal 55 section of a form of my invention adapted for manual operation only; Figure 4 is an

end elevation of a form of my invention adapted only for vacuum operation; and Figure 5 is a plan view of the inner face of the cylinder head 14 used in those forms of 60 my invention shown in Figures 1, 2, and 4.

As here shown the body portion 1 is made in the form of a flange adapted to align with and be clamped between the customary clamping flanges of the carburetor A and the 65 intake pipe B. As shown in Figure 2, the body portion 1 is transversely perforated with the usual bolt holes 2 and 2' and a central passage 3 which forms a part of the intake passage to the engine.

70 A perpendicular passage 4 leads outward from the central passage 3 and conjoins at its outer end with a smaller passage 5 which communicates with atmosphere. Intersecting the passages 4 and 5 at approximately 75 their juncture is another relatively large passage 6, conjoining near said intersection with a relatively small coaxial passage 7.

The outer end of the passage 7 communicates with a fuel supply pipe 8 which may be 80 led to any suitable source of fuel, it being shown in Figure 1 as connected with a T 9 to the fuel pipe C of the carburetor A.

The juncture of the passages 6 and 7 forms 85 a seat for a needle-valve 10, which is adapted to reciprocate in the passage 6. A coaxial enlargement of the outer end of the passage 6 forms a cylinder 11, adapted to coact with a piston 12, which is screw-threaded onto the outer end of the stem of the needle-valve 10 90 and locked in place by a nut 13.

The outer end of the cylinder 11 is closed by a head 14 which is retained by the screws 15 and 15', screw-threaded into bosses formed on the circumferential wall of the cylinder 11. 95

Between the cylinder-head 14 and the piston 12 is a compression-spring 16 which acts at all times to keep the needle-valve 10 seated against the mouth of the fuel passage 7.

That form of my invention shown in Figures 1, 2, 4 and 5 is adapted for vacuum operation when starting the engine. For this purpose the cylinder-head 14 is fitted with a passage 17 leading from its inner face to a vacuum pipe 18. The outer end of the pipe 18 communicates with the interior of the carburetor A at a point just inside the choke-valve D when in its closed position, as shown by the dotted lines in Figure 1.

The partial vacuum created in the carburetor A by operating the engine with the choke-valve D closed, acts through the pipe 18 and

the passage 17 to draw the piston 12 outward against the action of the spring 16, opening the needle-valve 10 and admitting fuel to the intake pipe B via the passages 6, 4 and 3.

5 As soon as the choke-valve D is released, the partial vacuum is relieved, permitting the spring 16 to return the piston 12 and the needle-valve 10 to their original positions and cut off the supplemental supply of fuel.

10 In some cases it is desirable to admit a supplemental supply of fuel to compensate for a temporary deficiency in the regular supply when the throttle is quickly opened. My invention may be adapted for this purpose 15 by the provision of an additional cylinder 19, the inner or closed end of which communicates with the inner end of the cylinder 11 by way of a passage 20. Mounted for reciprocation within the cylinder 19 is a piston 21, affixed to a piston-rod 22 by means of two clamp-nuts 23 and 23'. The outer end of the piston-rod 22 is operatively attached to the throttle-arm E by means of a clip 25, and the body portion 1 of the device is so placed 20 that a movement of the throttle-arm E toward the "open" position of the throttle will cause an inward reciprocation of the piston 21, and vice-versa.

It is evident that when the throttle is 30 opened the consequent movement of the piston 21 will act to compress the air within the cylinder 19, this rise in pressure being transmitted through the passage 20 to the inner end of the cylinder 11, pushing the piston 12 outward against the action of the spring 16 and opening the needle-valve 10, thus admitting fuel through the passages 6, 4 and 3 into the intake pipe B.

In order to properly regulate the duration 40 of time for the admission of supplementary fuel, a vent 26 is provided from the inner end of the cylinder 19 to atmosphere. This vent permits the escape of the air compressed by the piston 21, the spring 16 returning the 45 needle-valve 10 to its seat as soon as the pressure behind the piston 12 is released. The vent 26 is restricted by a screw 27 which may be moved upward or downward to cover or uncover it to any desired degree, thus governing 50 the rate at which the pressure behind the piston 12 is released.

The small air passage 5 is continuously open to atmosphere and is so placed relative to the mouth of the fuel passage 6 that the 55 blast of air induced through it serves to atomize and aerate the incoming fuel at all times, thus delivering it to the intake pipe B in the best condition for distribution and combustion.

60 Figure 3 shows a form of my invention adapted for use where manual operation is desirable. It differs from those heretofore described in that the cylinder 11 and the cylinder-head 14 are replaced by a cap 28 65 which is screw-threaded onto an extended

boss on the body 1, and a washer 29 is substituted for the piston 12.

The outer end of the stem of the needle-valve 10 extends through the cap 28 and is adapted for the attachment of manual operating means, that shown comprising a looped end of a pull-wire inserted through a transverse bore in the extended stem of the needle-valve 10.

Having thus described the purposes, construction and operation of an improved supplementary fuel feeding device for internal combustion engines, I claim as my invention—

1. A supplementary fuel feeding device 80 adapted for attachment to the intake pipe of an internal combustion engine having a choke-valve or throttle and throttle-operating mechanism, comprising a source of fuel, a relatively small fuel inlet passage and a relatively small air inlet passage converging toward a common center, a relatively large outlet passage diverging from this common center, a needle-valve in axial alignment with and adapted to seat against the mouth of said fuel inlet passage, a resilient element adapted to normally retain said needle-valve against its seat, and vacuum actuated means operable to move said needle-valve away from its seat when said engine is operated with said choke-valve closed, together with instrumentalities actuated from said throttle-operating mechanism and adapted to move said needle-valve away from its seat when said throttle is 90 opened.

2. A supplementary fuel feeding device for 95 attachment to the intake pipe of an internal combustion engine having a throttle and throttle-operating mechanism, comprising a source of fuel, a relatively small fuel inlet passage and a relatively small air inlet passage converging toward a common center, a relatively large outlet passage diverging from this common center, a needle-valve coaxial 105 with and adapted to seat against the mouth of said fuel inlet passage, a resilient element adapted to normally press said needle-valve against its seat, and means operable to move said needle-valve away from its seat, together 110 with instrumentalities actuated from said throttle-operating mechanism to move said needle-valve away from its seat when said throttle is opened, and additional means acting to permit said resilient element to gradually return said needle-valve to its seat.

3. In a fuel-feeding system for an internal combustion engine having an intake-pipe, a carburetor, a throttle-valve and a choke-valve adapted to form a vacuum in said intake pipe; in combination, a supplemental fuel-feeding 115 device adapted for attachment to said intake-pipe and having a relatively small fuel-inlet passage, a relatively small air-inlet passage adapted to discharge adjacent thereto, and a relatively large mixture-outlet communicat- 120 125 130

ing with the interior of said intake-pipe, together with an element operable to control the flow of fuel from said fuel-inlet passage and vacuum-actuated means to operate said element, said vacuum being obtained from between said throttle-valve and said choke-valve.

4. A supplementary fuel feeding device for internal combustion engines having an intake pipe and a choke-valve, a throttle and throttle-operating mechanism, comprising a source of fuel, a relatively small fuel inlet passage, a relatively small air inlet passage opening adjacent thereto, a relatively large outlet passage communicating with the interior of said intake pipe, a valve adapted to close said fuel inlet passage, a resilient element adapted to normally retain said valve in its closed position and vacuum-actuated means operable to open said valve when said engine is operated with said choke-valve closed, together with instrumentalities actuated by said throttle-operating mechanism to open said valve when said throttle is opened.

5. A supplementary fuel feeding device for internal combustion engines having an intake pipe and a choke-valve, a throttle and throttle-operating mechanism, comprising a source of fuel, a relatively small fuel inlet passage, a relatively small air inlet passage opening adjacent thereto, a relatively large outlet passage communicating with the interior of said intake pipe, a valve adapted to close said fuel inlet passage, a resilient element adapted to normally retain said valve in its closed position and vacuum-actuated means operable to open said valve when said engine is operated with said choke-valve closed, together with instrumentalities actuated by said throttle-operating mechanism to open said valve when said throttle is opened and means adapted to

permit said resilient element to gradually close said valve.

6. A supplementary fuel feeding device for internal combustion engines having an intake pipe and a choke valve, a throttle and throttle-operating mechanism, comprising a source of fuel, a relatively small fuel inlet passage, a relatively small air inlet passage opening adjacent thereto, a relatively large outlet passage communicating with the interior of said intake pipe, a valve adapted to close said fuel inlet passage, a resilient element adapted to normally retain said valve in its closed position and vacuum-actuated means operable to open said valve when said engine is operated with said choke-valve closed, together with instrumentalities actuated by said throttle-operating mechanism to open said valve when said throttle is opened and means adapted to permit said resilient element to gradually close said valve, said means being adjustable to vary the rate at which said resilient element is permitted to close said valve.

7. Supplemental fuel feeding means for a gas engine having an intake manifold and a carburetor which contains a throttle and a choke valve, comprising a casing having a passage communicating with the interior of said manifold, a fuel duct leading into said passage, an opening from atmosphere into said passage adjacent said fuel duct, a valve adapted to close said fuel duct, a piston mounted on the stem of said valve, and adapted to lift same, a spring arranged to seat said valve, a cylinder surrounding said piston and having an opening from atmosphere into its valve-end, and a passage leading from its opposite end to the interior of said carburetor between said throttle and said choke valve.
